UNITED STATES PATENT OFFICE.

HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

FLUID-TRANSLATING DEVICE.

Application filed April 12, 1921. Serial No. 460,852.

To all whom it may concern:

Be it known that I, HENRY F. SCHMIDT, a citizen of the United States, and a resident of Swarthmore, in the county of Delaware and State of Pennsylvania, have invented a new and useful Improvement in Fluid-Translating Devices, of which the following is a specification.

My invention relates to ejecting apparatus and more particularly to apparatus employed for removing non-condensable gases or vapors from condensers or similar apparatus. It has for an object the provision of an ejecting apparatus, including a number of stages or ejectors operating in series, in which means are employed for condensing the motive fluid delivered to each stage of the apparatus so that subsequent stages compress only non-condensable gases or vapors delivered from previous stages, and in which means are employed for proportioning the amount of work imposed upon each stage of the apparatus so that each stage does a definite proportion of the work of compression under all conditions. It has for a further object the provisions of a multi-stage ejecting apparatus in which improved means are employed for heating a liquid, such for example, as feed water.

These and other objects I attain by means of apparatus embodying features herein described and illustrated in the accompanying drawing in which the single figure is a diagrammatic sectional view of a multi-stage ejecting device embodying my invention.

Referring to the drawings, the apparatus illustrated includes ejectors 10, 11, 12, of any suitable type, discharging respectively, into inter-coolers, or contact condensers, 13, 14, 15. Each of the ejectors receives motive fluid, such as steam, from any suitable source through a pipe 16 and discharges it through a nozzle 17 into and through an entraining chamber 18 and into a diffuser 19. The outlet of each of the diffusers 19 of the ejectors 10, 11, 12 is shown connected to a pipe 21 which extends into and terminates below the surface of the water contained within the associated inter-coolers, suitable slots or perforations 22 being provided in the pipes 21 to secure an even distribution of the fluid and a noiseless condensation of the steam.

The inter-cooler 13 normally receives water from a hot well discharge pump 25 through a pipe 26 which is provided with a

check or non-return valve 27. The inter-cooler 13 is also provided with an overflow pipe 28 which communicates with the lower portion of the second stage inter-cooler 14. Water may also be delivered to the inter-cooler 13 through a delivery pipe 30 which communicates with any source of cold water supply, as for example an elevated tank 31, and is adapted to be employed only when the supply of water through the pipe 26 is insufficient. The pipe 30 is provided with a check valve 32 which is dependent in its operation upon the operation of the check valve 27, the two valves being so arranged that valve 32 will open as the valve 27 closes, and, vice versa, will close as the valve 27 opens, so that the amount of water delivered to the inter-cooler 13 will be maintained constant, irrespective of variations of flow through the pipe 26. Any suitable connection between the valves 27 and 32 may be employed. As shown, levers 33, 34 operatively secured to the valves 27 and 32 respectively, are connected by a rod 35.

The entraining chamber of the ejector 10 communicates through a port 37 with a condenser, or with a receptacle from which non-condensable gases or vapors are to be removed. The upper portion of the inter-cooler 13 communicates with the entraining chamber of the second stage ejector 11 through a pipe 38. The diffuser outlet of the second stage ejector 11 communicates through a pipe 21 with the inter-cooler 14, the outlet end of the pipe 21 being submerged in the water contained within the inter-cooler 14, as above described. The inter-cooler 14, like the inter-cooler 13 is provided with an over-flow pipe 39 which communicates with the lower portion of the third stage inter-cooler 15, and also with a non-condensable discharge pipe 40 through which the gases are led from the upper portion of the inter-cooler 14 to the third stage ejector 12. The third stage ejector 12 discharges into the lower portion of the inter-cooler 15, the non-condensable portions collecting in the upper part of the inter-cooler whence they are discharged through a relief valve 41 to the atmosphere. An over-flow pipe 42 serves to carry away the excess water from the inter-cooler 15 to a suitable storage receptacle.

In describing the operation of the arrangement of the apparatus above described,

the multi-stage ejecting device is considered as employed in connection with a condenser in which a vacuum of substantially 29 inches of mercury, referred to as a 30 inch barometer, is maintained, but with no idea of limiting the application of my invention to use in connection with condensers. Under such conditions, it is desirable to proportion the amount of work done in exhausting non-condensable gases from the condenser among the several ejectors, and to maintain the ratio of work done by each ejector constant.

Let it be assumed, for the purposes of illustration, that the ejectors 10, 11 and 12 are each designed to effect a compression of the non-condensable gases of 5 pounds per square inch absolute. With the pressure within the inter-cooler 15 maintained at 15 pounds per square inch absolute, the inter-coolers 13, 14, 15 would need be so located that the height of the water level in the inter-cooler 14 is approximately 10 feet above that in the inter-cooler 15, and the water level in the inter-cooler 13 approximately 10 feet above that in chamber 14, all in order to secure a pressure difference of 5 pounds between the adjacent inter-coolers. Non-condensable gases are evacuated from the condenser through the inlet 37 and are discharged with the motive steam by the ejector 10 through the pipe 21 into the bottom of the inter-cooler 13. The steam issuing through the pipe 21 is condensed upon coming into contact with the water, thereby heating the water, for example, to 120 degrees Fahr., assuming the entrance temperature of the water to be about 80 degrees Fahr., while the non-condensable gases are collected in the upper portion of the inter-cooler 13. The pressure in the upper portion of the inter-cooler may be considered to be due to two factors, the vapor tension of the water corresponding to its temperature and the pressure of the air. Under these circumstances, the lowest absolute pressure capable of being maintained in the inter-cooler 13 above the water would be limited by the vapor tension of the water at a temperature of 120 degrees, or would be approximately 2½ pounds per square inch absolute. The second stage ejector 11 receives the non-condensable gases from the inter-cooler 13 and is so designed that it is capable of increasing the pressure of the gases by 5 pounds, or compressing the fluid to 10 pounds absolute pressure, the pressure normally maintained above the water in the inter-cooler 14. The steam and non-condensable gases, issuing from the diffusers of the second stage ejector 11, are delivered to the second stage inter-cooler 14. The steam is condensed in passing through the water in the inter-cooler 14 and heats the water to approximately 160 degrees Fahr. The non-condensable gases collecting above the water

are withdrawn by the third stage ejector 12 and discharged, together with the motive steam, into the inter-cooler 15. The steam from ejector 12 is condensed upon contacting with the water in inter-cooler 14 and heats the water to about 200 degrees Fahr. The non-condensable gases collecting above the water are discharged to the atmosphere through a relief valve set for a pressure of 15 pounds per square inch absolute in the present example, or for any pressure which it is desired to maintain within the inter-cooler 15.

With this arrangement, the second stage ejector 11 is incapable of reducing the pressure in the inter-cooler 13 below the pressure corresponding to the head of water existing between the level of water in the inter-cooler 14 and within the inter-cooler 13, since as soon as a lower pressure is attained in the inter-cooler 13, water from the inter-cooler 14 is forced upwardly through pipe 28 into the inter-cooler 13 and since its temperature, approximately 160 degrees Fahr., is much higher than that in the inter-cooler 13, the vapor tension will be increased and vapor will be given off within the inter-cooler 13, which will be delivered with the non-condensable gases to the second stage ejector 11. This will cause the capacity of the ejector 11 to be exceeded with a resultant building up of the pressure within the inter-cooler 13 until normal pressure conditions are reestablished. Pressure conditions will be maintained in a similar way between the inter-coolers 14 and 15, the temperature of the water within the inter-cooler 15, in the case assumed for illustration, being approximately 200 degrees Fahr. It will thus be seen that water at a suitable temperature for feeding directly to a boiler is obtained by the employment of my improved multi-stage ejector and that at the same time a simple and reliable means for definitely proportioning the work of compression among the several ejectors of the apparatus is provided.

It will be understood that the conditions of operation described above in connection with the apparatus illustrated are merely for purposes of illustration, and that the work of compression may be proportioned among the several ejectors as may be desired.

It is further apparent that any number of ejectors may be employed and that the work of compressing the fluid to be ejected from the condenser may be divided among the ejectors in the most efficient manner.

While I have shown my invention in but one form, it will be obvious to those skilled in the art that it is not so limited but is susceptible of various other changes and modifications, without departing from the spirit thereof, and I desire, therefore, that only such limitations shall be placed thereupon

as are imposed by the prior art or as are specifically set forth in the appended claims.

What I claim is:

1. In an ejecting apparatus, a plurality of ejectors operating in series, and means for definitely proportioning the work of compression among the ejectors. 5
2. In an ejecting apparatus, a plurality of ejectors operating in series, means associated with each ejector for condensing the motive fluid issuing from each ejector, and means for definitely proportioning the work of compression between the ejectors. 10
3. In combination in a multi-stage ejector, a plurality of ejectors operating in series, inter-coolers interposed between adjacent ejectors of the series, the inter-coolers being so connected and disposed with relation to each other that the work of compression is definitely proportioned among the several ejectors. 15
4. In combination in a multi-stage ejector, a plurality of ejectors operating in series, inter-coolers interposed between adjacent ejectors of the series, the inter-coolers being located at different levels, whereby predetermined pressure differences are maintained in the several inter-coolers and the work of compression is definitely proportioned among the several ejectors. 20
5. In combination in a multi-stage ejector, a plurality of ejectors operating in series, inter-coolers interposed between adjacent ejectors of the series, connections between adjacent inter-coolers for discharging excess liquid from each inter-cooler to an inter-cooler next in series, the inter-coolers being disposed at successively lower levels, whereby the work of compression is definitely proportioned among the several ejectors. 25
6. In combination in a multi-stage ejector, an ejector the inlet of which communicates with a source of fluid to be ejected, an inter-cooler communicating with the discharge of said ejector, a second ejector communicating with the inter-cooler, a second inter-cooler communicating with the discharge of said second ejector, and a connection between the inter-coolers for delivering excess liquid from the first to the second inter-cooler, the first inter-cooler being at a pre-determined higher level than the second inter-cooler, whereby the work of compression is definitely proportioned between the two ejectors. 30
7. In an ejecting apparatus, a series of ejectors, each having an entraining chamber, a contact condenser for each ejector adapted to be partially filled with water and into which an ejector discharges, means for supplying fluid to be compressed to the entraining chamber of the first of said series of ejectors, means for conveying non-condensable gases from each of the contact condensers, except the final one, to the entraining chamber of the ejector next in series, conduits forming communication between the water containing portions of the adjacent contact condensers, said condensers being disposed at successively lower levels, whereby the work of compression is definitely proportioned among the several ejectors. 35
8. In an ejecting apparatus, a series of ejectors having an entraining chamber, a contact condenser for each ejector adapted to be partially filled with water and into which an ejector discharges, means for supplying fluid to be compressed to the entraining chamber of the first of said series of ejectors, means for conveying non-condensable gases from each of the contact condensers, except the final one, to the entraining chamber of the ejector next in series, and means associated with the condenser for proportioning the work of compression between the several ejectors. 40
9. In an ejecting apparatus, a series of ejectors having an entraining chamber, a contact condenser for each ejector adapted to be partially filled with water and into which an ejector discharges, means for supplying fluid to be compressed to the entraining chamber of the first of said series of ejectors, means for conveying non-condensable gases from each of the contact condensers, except the final one, to the entraining chamber of the ejector next in series, said condensers being disposed at successively lower levels, and means associated with the condensers for proportioning the work of compression between the several ejectors. 45
10. In an ejecting apparatus, a series of ejectors having an entraining chamber, a contact condenser for each ejector adapted to be partially filled with water and into which an ejector discharges, means for supplying fluid to be compressed to the entraining chamber of the first of said series of ejectors, means for conveying non-condensable gases from each of the contact condensers, except the final one, to the entraining chamber of the ejector next in series, said condensers being disposed at successively lower levels, conduits forming communication between the water containing portions of the adjacent contact condensers, and so arranged as to utilize the hydrostatic head between the condensers to proportion the work of compression between the several condensers. 50
11. In an ejecting apparatus, a plurality of ejectors operating in series, a contact condenser associated with each ejector and adapted to contain a body of water, means for discharging the fluids from each ejector into its associated condenser, means for withdrawing the non-condensable gases 55

from each condenser into the ejector next in the said series and for discharging the said gases from the condenser associated with the last of said series of ejectors, conduits extending from the water level of each condenser to the bottom of the condenser next in series, said condensers being disposed at successively lower levels, whereby the work of compression is definitely proportioned among the several ejectors.

12. In an ejecting apparatus, a plurality of ejectors operating in series, a contact condenser for each ejector into which the latter discharges, means for supplying fluid at a subatmospheric pressure to the first of said series of ejectors, means for conveying non-condensable gases from each contact condenser, except the final one, to the ejector

next in series, means for delivering water to the first of said condensers, means for delivering excess water from each condenser, except the last one, to a condenser next in series, means for maintaining predetermined successively higher pressures in the condensers, the pressure in the final condenser being substantially atmospheric pressure, and means for discharging non-condensable gases and water from the final condenser, whereby the work of compression is definitely proportioned among the several ejectors.

In testimony whereof, I have hereunto subscribed my name this 1st day of April, 1921.

HENRY F. SCHMIDT.
